UNITED STATES PATENT OFFICE.

CHARLES FLEISCHER, OF BROOKLYN, NEW YORK, ASSIGNOR TO GEORGE W. G. BOYCE,
OF YONKERS, NEW YORK.

AMUSEMENT DEVICE.

Application filed February 19, 1925, Serial No. 10,393. Renewed February 9, 1926.

To all whom it may concern:

Be it known that I, CHARLES FLEISCHER, a citizen of the United States, and a resident of the city of New York, borough of Brooklyn, in the county of Kings and State of New York, have invented a new and Improved Amusement Device, of which the following is a full, clear, and exact description.

10 This invention relates to amusement devices, an object of the invention being to provide a device in which a coin is manually manipulated so that if the operation is successful the coin will function to operate a latch and release the door of a compartment containing a prize. If the operation is unsuccessful the coin will drop into a cash compartment.

15 A further object is to provide a device of this character which may be located in public places, and which while affording amusement will require skill for the successful manipulation of a coin to secure a prize.

20 A further object is to provide a device of this character which can be manufactured and placed and sold at a reasonably low price, which will be ornamental and attractive in appearance, and which will most efficiently perform the functions for which it is intended.

25 With these and other objects in view, the invention consists in certain novel features of construction and combinations and arrangements of parts, which will be more fully hereinafter described and pointed out in the claims.

In the accompanying drawings—

Figure 1 is a view in front elevation illustrating my improved device;

30 Figure 2 is a view in vertical longitudinal section on the line 2—2 of Figure 1;

Figure 3 is a view in elevation of the inner face of the casting or device per se removed from its supporting cabinet;

35 Figures 4, 5, 6, 7, 8 and 9 are views in section on the lines 4—4, 5—5, 6—6, 7—7, 8—8 and 9—9 of Figure 1 of the drawings.

1 represents a metal plate or casting, and while I shall refer to the plate 1 as a "casting" it is to be understood that I use this term in its broadest possible sense to include a metal member constituting a single integral part which may be cast, drop forged, or formed in any other way to give the necessary shape thereto.

This plate 1 is secured preferably by hidden screws 2 to a removable front plate or door 3 of a cabinet 4. The front plate 3 may have dowels 5 at one end to fit in recesses 6 in the upper wall 7 of cabinet 4 and provided with a suitable lock 8 at its lower portion to engage the bottom 9 of the cabinet so that it requires the proper key to remove the plate or board 3 to gain access to the interior of the cabinet. This cabinet is 60 designed to be supported or suspended or otherwise secured in public places so that it is in convenient reach of the public.

The plate or casting 1 throughout its main portion is laterally offset from the plate or door 3 a distance greater than the thickness of the coin to be manipulated and with this end in view the edge portions 10 of plate 1 constitute flanges offset from the main portion of the plate and located flat against the 70 board or plate 3.

The upper portion of the plate 1 is provided with an opening 11 which is normally closed by a transparent door 12, the latter mounted adjacent its upper ends on suitable 80 hinge pins 13 to permit the lower end of the door to swing outwardly and expose a package or other prize 14 located in the compartment 15 in cabinet 4. This door 3 is normally held in closed position by a pivoted 85 latch bar 16, the latter being pivoted near its lower end as shown at 17, and its upper longer end adapted to be engaged behind a lip or shoulder 18' on the door 12 to hold the latter in closed position. A coil spring 90 18 connects a projection 19 on the latch bar 16 with a fixed member 20 on plate 1 so as to exert pressure on the latch bar to normally hold it in locked position.

A transparent plate 21 covers the intermediate portion of the plate 1 and is secured back of rabbeted enlargements 22 on the plate 1 so that it cannot be removed from the outside. The lower end of the latch bar 16 projects into the space back of the transparent plate 21 so that it can be seen, and adjacent the lower end of said latch bar an arrow 23 is formed on the plate and constitutes an embossed member thereon which indicates the position the coin must be manipulated to release the latch and also provides a shoulder against which the coin can be pressed in order to move the latch.

The plate 1 back of the transparent plate 21 is provided with a pair of arcuate raised 110

or integrally embossed members 24 constituting a pocket for the reception of a coin 25 therein. An opening 26 is formed in the plate 1 above the transparent plate 21 to receive the coin and a raised guide 27 is formed on the plate to direct the coin from the opening 26 back of the transparent plate 21 into the pocket formed by the members 24.

10 The lower portion of the front plate is laterally offset inwardly, forming a recess 27' in which a manually movable bar 28 is located. This bar 28 projects through an opening 29 in the plate with its upper end 15 in position to engage a coin 30 when the latter is in the pocket 24. A knob or handhold 31 is formed on the lower end of the lever to facilitate its manipulation.

In operation a coin 30 is projected through 20 the opening 26 and falls into the pocket 24. The operator then manipulates the bar 28, balancing the coin thereon and endeavoring to move the same to the dotted line position indicated in Figure 1, and when in this 25 position a continued pressure will move the latch bar to its releasing position to allow the door 12 to swing open. If the coin falls off of the upper end of the bar 28 during the manipulation thereof it will drop 30 through any of a series of openings 32 in the plates 1 and 3 and fall into the interior of the cabinet and be kept.

To compel the door to swing to open 35 position when released, I provide a curved arm 33 fixed to a shaft 34 mounted in plate 3. A crank arm 35 is provided on the shaft 34 and a coil spring 36 connects this crank arm with a fixed pin 37 tending to move the shaft 34 in a direction to force the arm 33 40 against the door and move it outwardly a short distance and hold it in this position until it is manually moved to complete open position for the removal of the prize or package 14.

45 A weight 38 also preferably extends downwardly from the shaft 34 so as to overcome any tendency toward over-movement or momentum due to the action of the spring.

After the package is removed it is necessary to insert a new one in the compartment 50 15 and to return the door to its latched position, ready for a new operation.

Various slight changes and alterations 55 might be made in the general form of the parts described without departing from the invention, and hence I do not limit myself to the precise details set forth but consider myself at liberty to make such slight changes and alterations as fairly fall within the 60 spirit and scope of the appended claims.

I claim:

1. An amusement device including a movable door adapted to close a compartment, a latch holding said door in closed position, and a coin balancing and manually operated

manipulating member adapted to move a coin into position to release the latch.

2. An amusement device, including a movable door adapted to close a compartment, a latch holding said door in closed position, a coin balancing and manually operated manipulating member adapted to move a coin into position to release the latch, and a transparent cover, back of which the coin is manipulated so that it can be observed from the outside.

3. A device of the character described, comprising a plate adapted to be secured to a cabinet, a hinged transparent door mounted in the plate, a spring held latch normally locking the door in closed position, a transparent plate secured to the first-mentioned plate and spaced therefrom a distance slightly greater than the thickness of the coin, a coin pocket formed back of the transparent plate, means permitting the positioning of a coin in said pocket, and a manually movable member operated from outside of the plate and adapted to engage the coin and move it to a position to engage and release the latch.

4. A device of the character described, comprising a plate adapted to be secured to a cabinet, a hinged transparent door mounted in the plate, a spring held latch normally locking the door in closed position, a transparent plate secured to the first-mentioned plate and spaced therefrom a distance slightly greater than the thickness of the coin, a coin pocket formed back of the transparent plate, means permitting the positioning of a coin in said pocket, a manually movable member operated from outside of the plate and adapted to engage the coin and move it to a position to engage and release the latch, and a member located adjacent the latch and between which and the latch a coin is adapted to be forced to release the latch.

5. A device of the character described, comprising a plate adapted to be secured to a cabinet, a hinged transparent door mounted in the plate, a spring held latch normally locking the door in closed position, a transparent plate secured to the first-mentioned plate and spaced therefrom a distance slightly greater than the thickness of the coin, a coin pocket formed back of the transparent plate, means permitting the positioning of a coin in said pocket, a manually movable member operated from outside of the plate and adapted to engage the coin and move it to a position to engage and release the latch, a member located adjacent the latch and between which and the latch a coin is adapted to be forced to release the latch, said first-mentioned plate having an offset recessed portion in which the said movable member is exposed, and a knob or handhold on the lower end of said movable

member adapted to be moved in various positions in the recess in order to balance and manipulate a coin in endeavoring to engage the latch.

5 6. An amusement device including a compartment having a door, means tending to open the door, a latch normally holding the door in closed position, a manually movable member, means for directing a coin onto one end of said member and said member adapted to move and balance the coin into engagement with the latch to release the door from locked position.

7. An amusement device, including a compartment, a transparent door for said compartment disclosing the contents thereof, a latch normally holding the door in locked position, a transparent plate, means for manually manipulating a coin back of the transparent plate in an endeavor to operate the latch, said means operated from a position outside of the device, and said device having openings therein through which the coin falls if the operator fails to properly manipulate the same.

CHARLES FLEISCHER.
